US00D592099S

(12) **United States Design Patent**
Longpre et al.

(10) **Patent No.:** **US D592,099 S**
(45) **Date of Patent:** **** May 12, 2009**

(54) **SNOWMOBILE**

(75) Inventors: **Guillaume Longpre**, Granby (CA);
Martin Portelance, Chicoutimi (CA);
Etienne Guay, Orford (CA)

(73) Assignee: **Bombardier Recreational Products Inc.**, Valcourt (CA)

(**) Term: **14 Years**

(21) Appl. No.: **29/299,911**

(22) Filed: **Jan. 7, 2008**

(51) **LOC (9) Cl.** **12-14**

(52) **U.S. Cl.** **D12/7**

(58) **Field of Classification Search** **D12/7, D12/8, 9, 10, 110, 111, 112, 307, 400, 86, D12/85, 88, 11, 159, 162, 168, 169, 172, D12/173; D21/533; 180/182, 190, 184-186, 180/9.25, 180, 219, 193, 194; D6/354; 280/845**

(57) **CLAIM**

The ornamental design for a snowmobile, as shown and described.

DESCRIPTION

FIG. 1 is a front left perspective view showing a snowmobile according to our design;

FIG. 2 is a left side elevation view thereof;

FIG. 3 is a right side elevation view thereof;

FIG. 4 is a rear elevation view thereof;

FIG. 5 is a front elevation view thereof; and,

FIG. 6 is a top plan view thereof.

Throughout the Figures, broken lines showing structure are for illustrative purposes only and form no part of the claimed design. Portions of the snowmobile not shown in the Figures form no part of the claimed design.

1 Claim, 6 Drawing Sheets
